CLAIM

The ornamental design for the pivoted jaw wrench, as shown and described.

DESCRIPTION

FIG. 1 is a front elevational view of the "pivoted jaw wrench" showing my new design, the rear view being a mirror image;

FIG. 2 is a top plan view thereof;

FIG. 3 is a bottom plan view thereof;

FIG. 4 is a right side elevational view thereof;

FIG. 5 is a left side elevational view thereof; and
FIG. 6 is a sectional view thereof, taken along line 6—6
of FIG. 4.

FIG. 1

FIG. 2

FIG. 3

FIG. 4

FIG. 5

FIG. 6
